UNITED STATES PATENT OFFICE.

JOHN D. PEDERSEN, OF JACKSON, WYOMING.

FIREARM.

1,297,109.

Specification of Letters Patent.

Patented Nov. 15, 1921.

Original application filed July 30, 1915, Serial No. 42,774. Renewed July 17, 1919, Serial No. 311,689.
Divided and this application filed December 12, 1919. Serial No. 344,419.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which are usually 10 designated as small-arms, and a principal object of the invention is to furnish an improved magazine retaining and releasing device, or magazine-lock, particularly applicable to auto-loading and automatic pistols

15 One class of small-arms to which my present improvements are applicable, includes the auto-loading pistols in which a magazine of tubular form, or cartridge carrier, is removably secured within the grip, or 20 handle-portion of the frame or receiver of the firearm. An improved auto-loading pistol of this kind is described in my Patent No. 1,348,733, dated August 3, 1920, and granted on my copending application (re- 25 newal) Serial No. 311,689, filed July 17, 1919, and the improvements herein described and claimed are also illustrated in my said patent, but are not claimed therein. Therefore, for convenience of illustration, I have 30 herein illustrated my present improvements as arranged and applied to the particular kind of auto-loading pistol which is shown in the drawings of said patent, to which reference may be had.

35 In the accompanying drawings forming a part of this specification, Figure 1 is a side elevation of an auto-loading pistol furnished with my present improvements; this view is a left-hand side view corresponding generally with the left-hand side view shown in Fig. 1 of said patent.

Fig. 2, is a sectional view of a portion of an auto-loading pistol and of the magazine chamber thereof, my magazine-lock partly 45 in outline, and showing in outline a portion of a cartridge-receptacle or holder in the magazine chamber of the pistol having means for engaging the receptacle or holder with my magazine-lock.

50 Fig. 3, is a sectional top or plan view of a portion of the frame of an auto-loading pistol comprising a portion of the magazine chamber of the pistol, my magazine-lock,

and a portion of a cartridge-receptacle or holder, the receptacle or holder being locked 55 in the magazine chamber.

Fig. 4, is a sectional top or plan view of a portion of the frame of an auto-loading pistol comprising a portion of the magazine chamber of the pistol, my magazine-lock, 60 and a portion of a cartridge-receptacle or holder, the receptacle or holder being unlocked in the magazine chamber.

Fig. 5, is a sectional top or plan view of a portion of the frame of an auto-loading 65 pistol comprising a portion of the magazine chamber of the pistol, and my magazine-lock partly disengaged from said frame.

Fig. 6, is a sectional top or plan view of 70 a portion of the frame of an auto-loading pistol comprising a portion of the magazine chamber of the pistol, and my magazine-lock, the parts of my magazine-lock being partly disengaged from said frame and 75 from each other, and one of the parts being shown in outline as partly withdrawn from said frame.

Fig. 7, is a side view of one of the parts 80 of my magazine-lock.

Fig. 8, is a view of the upper end of said part.

Fig. 9, is a view of the lower end of said part.

Fig. 10, is a rear view of said part. 85

Fig. 11, is a front view of said part.

Similar characters designate like parts in all the views.

My magazine-lock denoted generally by A, comprises a locking-portion m and a lower or locking-pin 13^t. The locking portion m, is of cylindrical shell form, and is provided in its rear side with an inwardly curved or concave recess, 15, the purpose of which is to conform to and receive the adjacent edge of a removable cartridge receptacle or holder, such as R, which edge is usually of a substantially convex form, and which receptacle or holder is insertable in the magazine chamber M. By front and 95 rear side, here and elsewhere herein, is meant the side of my magazine-lock as related to the frame or receiver B, toward the muzzle or toward the rear of the pistol of which such frame or receiver is a portion. 100 105

The locking-portion m has a rearwardly

extending projection or ledge 13^k, which snaps into a suitably located cut or notch m^2 , in the adjacent wall or case of the cartridge receptacle or holder when the 5 same is inserted in the magazine chamber M. The locking portion m, has on its front side at the outer and inner ends a semicircular groove 16, and a recess 13^a, which are hereinafter more fully described.

10 By outer and inner end, here and elsewhere herein is meant, the end of my magazine-lock as related to the right or left hand side of the frame or receiver B, of the pistol when the pistol is in firing position, 15 and of which pistol such frame or receiver is a portion.

The follower or locking-pin 13^f, comprises a cylindrical body-portion, 17, and a spring 13^j. The body-portion 17, is provided near its inner end with a flanged head 13^m. The spring 13^j, preferably is a helix spring and is arranged around the body-portion 17 inwardly of the flanged head 13^m, and bearing at one end upon the 25 flanged head 13^m, the purpose of the spring 13^j, being hereinafter more fully described.

Suitable intersecting holes or apertures t^7 and t^8 , Figs. 1 and 2, are formed in the frame or receiver B, of the pistol to hold 30 the locking-portion m and the follower 13^f in proper relation to each other, and also to prevent my magazine lock M from turning or revolving in the frame or receiver B, when the parts m and 13^f, are inserted in 35 their respective holes and are in operative engagement.

To assemble the parts of my magazine-lock the locking-portion m is inserted in the hole or orifice t^7 , from the outer or 40 right hand side of the frame or receiver B, the outer end of the locking-portion m, being tilted forwardly relative to the frame or receiver B, so that the outer end of the concave recessed front side of the locking-portion m will lie in the path of the cylindrical body-portion 17, and the inner end 45 of the concave recessed front side of the locking-portion m, when the body-portion 17, is inserted in the hole or aperture t^8 , 50 will lie out of the path of the body-portion 17.

The cylindrical body-portion 17 is inserted in the hole or aperture t^8 , from the inner or left hand side of the frame or receiver 55 B, and pushed inwardly until the right hand end of the spring 13^j, comes in contact with the interior surface, 18, of the frame or receiver B, the holes t^7 and t^8 , being arranged to provide for such contact.

60 The other end of the spring 13^j, bears on the flanged head 13^m, of the body-portion 17, the pressure of the spring 13^j, being to thrust the body-portion 17, toward the inner side or left hand side of the frame or receiver B. The spring 13^j, when the lock-

ing-portion m, and the follower 13^f, are locked together in operative relation being intended to hold these parts in this relation, and also to permit the moving or pushing outwardly, or toward the right 70 hand side of the frame or receiver B, of the locking-portion m and the follower 13^f, while locked together, to release the ledge 13^k, from engagement with the cartridge-receptacle or holder R, for the removal of 75 such receptacle or holder from the magazine chamber M; and, when outward pressure on the locking-portion m and follower 13^f, is relieved to move the locking-portion and follower inwardly, or to the left, to 80 reengage the ledge 13^k, with the cartridge-receptacle or holder R, to retain the same in the magazine chamber M, Figs. 3 and 4. The outer end of the locking-portion m, is then tilted toward the rear of the frame or 85 receiver B, the concave recessed front side of the locking-portion m, thus being partially engaged with the cylindrical body-portion 17, and the notch or recess 13^a, of the locking-portion m being substantially in line 90 with the flanged head 13^m, of the body-portion 17, and snapping into engagement with the flanged head 13^m, my magazine-lock assuming the position shown in Fig. 3.

The edges of the concave recessed front 95 side of the locking-portion m, are inclined toward the rear of the frame or receiver B, to provide clearance for the spring 13^j.

To insert a cartridge receptacle or holder, such as R, in the pistol my magazine-lock 100 is pressed outwardly, or toward the right hand side of the frame or receiver B, and so held until the projection or ledge 13^k, of the locking-portion m is drawn out of the path of the cartridge receptacle or holder 105 as it is inserted in the magazine chamber of the pistol.

The cartridge receptacle or holder is pushed into the magazine chamber M, usually from the bottom thereof, upwardly, 110 pressure of my magazine-lock is released and as upward push on the cartridge receptacle or holder is continued the projection or ledge 13^k, snaps into the recess or notch m^2 , in the cartridge receptacle or holder, and thereby prevents upward or downward movement of the receptacle or holder, or unintentional removal thereof from the magazine chamber of the pistol, Figs. 3, 4, 5, and 6.

To disassemble my magazine-lock, the 120 same being in the position shown in Fig. 3, the magazine-lock is pushed outwardly, or toward the right hand side of the frame or receiver B, until the ledge 13^k of the locking-portion m, is disengaged from the notch or 125 recess M^2 , of the cartridge receptacle or holder, Fig. 4. The cartridge receptacle or holder is withdrawn from the magazine chamber, the magazine lock is then pushed farther inwardly until the ledge 13^k is dis- 130

engaged from, or is outside of, the frame or receiver B, Figs. 5 and 6. The outer end of the locking-portion *m* is then tilted forwardly, and the body-portion 17 of the following 13¹, is withdrawn from the inner or left hand side of the frame or receiver B, and the locking-portion *m* is withdrawn from the outer or right hand side of the frame or receiver B.

10 I thus provide a magazine-lock which may be assembled or disassembled by finger manipulation and entirely without the use of a tool.

The exterior surfaces of the ends of my
15 magazine lock may be roughed or cross-hatched for convenience of manipulation.

Having thus described my invention, I claim:

claim:

1. In a firearm, in combination, a frame of said firearm, a magazine chamber formed by said frame, a cartridge receptacle insertible in said chamber, and a magazine lock comprising a locking-portion and a follower; said magazine lock being adapted to be inserted in said frame and prevented from revolving therein by engagement of the ends of said locking-portion and said follower with said frame; said magazine lock when inserted in said frame being engageable with said cartridge-receptacle to prevent or permit removal thereof when the same is inserted in said chamber.

2. In a firearm, in combination, a frame of said firearm having holes in opposite sides thereof, a magazine chamber formed by said frame, a cartridge receptacle removably insertible in said chamber and a magazine lock insertible in said frame comprising a locking portion and a follower; said magazine lock being prevented from revolving in said frame by engagement of respective opposite ends of said locking portion and said follower with respective holes in opposite sides of said frame, said magazine lock when inserted in said frame being engageable with said cartridge-receptacle to prevent or permit removal thereof when the same is inserted in said chamber.

5 said frame as inserted in said chamber.

3. In a firearm, in combination, a frame of
50 said firearm having intersecting holes in op-
posite sides thereof, a magazine chamber
formed by said frame, a cartridge receptacle
removably insertible in said chamber, and a
magazine lock comprising a locking-portion
55 and a follower; said magazine-lock being
adapted to be inserted in said frame and
prevented from revolving therein by engage-
ment of the ends of said locking portion and
said follower with said intersecting holes;

60 said magazine lock being adapted when in-
serted in said frame to engage said cartridge-
receptacle to prevent or permit removal
thereof when the same is inserted in said
chamber.

65 4. In a firearm, in combination, a frame

of said firearm, a magazine chamber formed by said frame, a cartridge receptacle removably insertible in said chamber, and a magazine lock insertible in said frame comprising a locking-portion and a follower; said locking-portion having means on one side thereof for engaging said follower and having means on the other side thereof engageable with said cartridge receptacle when the same is inserted in said chamber; said magazine lock being adapted by engagement or disengagement of said locking-portion with said cartridge receptacle to prevent or permit removal of said cartridge receptacle from said chamber. 70 75 80

5. In a firearm, in combination, a frame of said firearm, a magazine chamber formed by said frame, a cartridge receptacle removably insertible in said chamber having means for engagement with the locking-portion of 85 a magazine lock, and a magazine lock insertible in said frame and movable therein comprising a locking-portion and a follower; said locking-portion having means on one side thereof for engaging said follower and 90 having means on the other side thereof engageable with said means for engagement of the cartridge receptacle when said receptacle is inserted in said chamber; said locking-portion and said follower being movable 95 together in operative relation to each other in said frame and arranged by movement together in said frame to engage or disengage said locking portion and said cartridge receptacle to prevent or permit removal of 100 said cartridge receptacle from said chamber.

6. In a firearm, in combination, a frame of said firearm, a magazine chamber formed by said frame, a cartridge receptacle removably insertible in said chamber having means for engagement with the locking-portion of a magazine lock, and a magazine lock insertible in said frame and movable therein comprising a locking-portion and a follower; said locking-portion having means on one side thereof for engaging said follower and having means on the other side thereof engageable with said means for engagement to the cartridge receptacle when said receptacle is inserted in said chamber; said follower being provided with spring means and means co-operatively engaging said locking-portion to retain said follower and said locking portion in operative relation movable in said frame, and by movement of said follower and said locking-portion in said frame to engage or disengage said locking portion and said cartridge receptacle to prevent or permit removal of said cartridge receptacle from said chamber. 125

7. In a firearm, in combination, a frame of said firearm, a magazine chamber formed by said frame, a cartridge receptacle removably insertible in said chamber having means for engagement with a magazine lock, and 130

a magazine lock insertible in said frame and movable therein comprising a locking portion and a follower; said locking-portion having means on one side thereof for engaging said follower and means for locking the locking-portion to said follower, and having means on the other side thereof for engaging said cartridge-receptacle and means engageable with said means for engagement 5 of the cartridge-receptacle when the same is inserted in said chamber; said follower being provided with a spring engaging said follower and engaging said frame and means coöperating with said locking means 10 of the locking-portion to retain said follower and said locking portion in operative relation removably in said frame, and by movement of said follower and said locking portion in said frame to engage or disengage 15 said locking-portion and said cartridge-receptacle to prevent or permit removal of said cartridge receptacle from said chamber.

8. In a firearm, in combination, a frame of said firearm, a magazine chamber formed by said frame, a cartridge receptacle removably insertible in said chamber having means for engagement with a magazine lock, and a magazine lock insertible in said frame and movable therein comprising a locking-portion and a follower provided with projection means for engagement; said locking portion having means on one side thereof for conformably engaging said follower and means for engaging said projection means of the follower, and having means on the other side thereof for conformably engaging said cartridge-receptacle and means engageable with said means for engagement of the cartridge-receptacle and means engageable with said means for engagement of the cartridge-receptacle when the same is inserted in said chamber; said follower being provided with a spring engaging said follower and said frame to retain said follower and said locking portion in operative relation movably in said frame, and by movement of said follower and said locking-portion in said frame to engage or disengage said locking portion and said cartridge-receptacle to prevent or permit removal of said cartridge receptacle from said chamber.

9. In a firearm, in combination, a frame of said firearm, a magazine chamber formed by said frame, a cartridge receptacle removably insertible in said chamber having means for engagement with a magazine lock, and a magazine lock insertible in said frame and movable therein comprising a locking portion and a follower provided with projection means for engagement; said locking-portion having means on one side thereof for conformably engaging said follower and means for engaging said projection means of the

follower, and having means on the other side thereof for conformably engaging said cartridge receptacle and means engageable with said means for engagement of the cartridge receptacle when the same is inserted in said chamber; said follower being provided with a spring engaging said follower and said frame to retain said follower and said locking-portion in operative relation movably in said frame, and by movement of said follower and said locking-portion to prevent or permit removal of said cartridge receptacle from said chamber; the respective ends of said locking-portion and said follower engaging respective opposite sides of said frame to prevent revolution of said magazine lock in said frame.

10. In a firearm, in combination, a frame of said firearm, a magazine chamber formed by said frame having a concave end wall, a cartridge receptacle removably insertible in said magazine having a convex end conforming to said concave end wall and having a recess on said convex end, and a magazine lock insertible in said frame and movable therein comprising a locking-portion and a cylindrical follower provided with a flanged head; said locking-portion having means on one side thereof for conformably engaging the convex end of said cartridge receptacle and a projection engageable with said recess in said convex end; said follower being provided with a spring engaging said flanged head and said frame to retain said follower and said locking-portion in operative relation movably in said frame, and by movement of said follower and said locking portion in said frame to engage or disengage said locking-portion and said cartridge receptacle to prevent or permit removal of said cartridge receptacle from said chamber.

11. In a firearm, in combination, a frame of said firearm having intersecting holes in opposite sides thereof, a magazine chamber formed by said frame having a concave end wall, a cartridge receptacle removably insertible in said chamber having a convex end conforming to said concave end wall and having a recess in said convex end, and a magazine lock insertible in said frame and movable therein comprising a locking-portion and a cylindrical follower having a flanged head; said locking-portion having means on one side thereof for conformably engaging said cylindrical follower and means for engaging said flanged head, and having on the other side thereof means for conformably engaging the convex end of said cartridge receptacle and a projection engageable with said recess in said convex end; said follower being provided with a spring engaging said flanged head and said frame to retain said follower and said locking-portion in operative relation movably in said

frame, and by movement of said follower and said locking-portion in said frame to engage or disengage said locking-portion and said cartridge receptacle to prevent or permit removal of said cartridge receptacle from said chamber; the respective ends of said follower and said locking portion en-

gaging intersecting holes in respective sides of said frame to prevent revolution of the magazine lock in said frame.
